(57) CLAIM

The ornamental design for a wall mounted mirror vanity, as shown and described.

DESCRIPTION

FIG. 1 is a front perspective view of a wall mounted mirror vanity;

FIG. 2 is a back perspective view thereof;

FIG. 3 front elevational view thereof;

FIG. 4 is a back elevational view thereof;

FIG. 5 is a first side elevation view thereof;

FIG. 6 is a second side elevation view thereof;

FIG. 7 is a top plan view thereof; and,

FIG. 8 is a bottom plan view thereof.

The broken lines in the drawings illustrate portions of the wall mounted mirror vanity that form no part of the claimed design.

1 Claim, 8 Drawing Sheets
